UNITED STATES PATENT OFFICE.

EDWARD C. MAGDEBURGER, OF WASHINGTON, DISTRICT OF COLUMBIA.

INTERNAL-COMBUSTION ENGINE.

Application filed January 20, 1925. Serial No. 3,604.

My invention relates broadly to internal combustion engines employing the two-stroke cycle and more particularly to a scavenging system therefor.

5 An object of my invention is to provide a system of scavenging that is simple, effective in operation, and economical in air consumption.

10 Another object is to provide means for efficient distribution of fuel charge in the combustion space to secure complete combustion.

15 A still further object is to prevent the heat of combustion from acting direct on the cylinder head thus protecting it from cracking due to heat stresses set in.

20 A further object is to eliminate the difficulties in keeping cool the outer surface of the piston rod in a double acting engine to permit its lubrication.

With the above and other objects in view the invention consists in the combination, construction and arrangement of parts as will be hereinafter more fully described.

25 Reference is to be had to the accompanying drawings forming part of this specification in which like reference characters indicate corresponding parts throughout the several views, except that "a" is added to similar parts of the lower cylinder in a double acting cylinder, and in which

30 Figure 1 is a cross sectional view of a double acting cylinder with my invention applied. In order to make it simpler to discuss the flow of the scavenging and exhaust fluids the cross sectional plane has been taken through the opening of the exhaust ports and then this cross sectional plane has been rotated about a vertical axis to include the 35 openings of the scavenging ports. It must be kept in mind that an exhaust port does not lie directly above a scavenging port.

Fig. 2 is a sectional plan view on the line A—A of Fig. 1,

40 Fig. 3 is a sectional view showing the piston in its top dead center,

45 Fig. 4 is a sectional view showing the position of the piston when scavenging in the upper cylinder begins and also showing the relative position of the exhaust and scavenging ports for the lower cylinder. The upper exhaust and scavenging ports have been rotated into the same plane as in Fig. 1 for the purpose of simplifying the 50 discussion of the flow of gases. The lower

scavenging and exhaust ports are shown in their true positions.

Fig. 5 is a cross sectional view of a crank case compression engine with my invention applied, and

55 Fig. 6 is a cross sectional view of a single acting cylinder with supercharging valves and my invention applied.

Referring more particularly to the drawings, cylinder 1 may either have a cylinder 60 head or be of the inverted cup type. There are two rows of ports 2 and 4 all around the periphery of the cylinder, arranged in staggered relation to each other, as clearly 65 shown in Fig. 4. The ports 2 are connected with the exhaust manifold 3 and the ports 4 communicate with the scavenging air receiver 5. The piston consists of the conventional head 6, piston rings 7, and an auxiliary head 8, which may be cast in one piece 70 with head 6 or suitably fastened thereto, but separated therefrom by a cylindrical wall having a number of ports 9, these ports corresponding in number, relative location and substantially in shape to the scavenging 75 ports 4 in the cylinder wall, which they match when the piston is in the dead center position. It will be seen from Fig. 2 that the ports 9 are arranged substantially tangential to the mean diameter of the chamber 80 10 formed between the piston head 6 and auxiliary head 8.

85 The action of the system begins when the upper edge 11 of the auxiliary head 8 (see Fig. 4, action of the piston being in the direction of the arrow) reaches the upper edge 90 of the exhaust ports 2. It will be noted that prior to that these ports were closed by the wall 12 separating the heads 6 and 8. As soon as the edge 11 arrives at the position 95 above stated the exhaust ports open and the exhaust gases rush into the chamber 13 which surrounds the cylinder, and the pressure in the cylinder drops to about atmospheric. Immediately after the edge 14 of the piston head 6 leaves the upper edge of the ports 4 scavenging air enters the chamber 10 through the ports 9, which, because 100 of their tangential incline, create a whirl in the incoming scavenging air. This whirling motion continues even after the air leaves the piston chamber through an opening 15 in the auxiliary head 8, forming a column which advances toward the end of the cylinder displacing the products of combustion 110

until it impinges on the cylinder head when the air changes direction and continues to displace the products of combustion along the cylinder wall and finally passes into the 5 exhaust ports. Thus the cylinder will be completely scavenged with minimum loss of scavenging air into the exhaust. Direct loss from scavenging ports into exhaust ports, inevitable in all the commonly used 10 systems of scavenging, is effectively prevented by the baffling action of the auxiliary head 8.

Scavenging will continue as long as the 15 scavenging ports in the cylinder are open, but compression will begin as soon as the exhaust ports are closed.

As will be seen the larger part of the air charge is in the cylinder at the beginning of the compression and must enter the chamber 10 through the opening 15, which, just before the dead center position of the piston, is materially reduced by the protruding part 16 of the cylinder head, or fuel valve, thus forcing an accumulation of pressure on top 25 of head 8 and causing a stream of considerable velocity to enter the chamber 10. This action produces lively air circulation and causes socalled turbulence in the piston chamber which now becomes combustion 30 chamber with the introduction of fuel from the fuel valve. Turbulence is a well recognized aid to complete combustion.

An important feature of my invention is that the heat of the combustion never strikes 35 the surface of the cylinder head, being separated from it by compressed air on top of the auxiliary head 8, thus the cylinder head is well protected and not subject to heat cracks.

40 Due to the necessity of directing the scavenging air upwards in most of the designs of two cycle engines, this air does not come in contact with the top surface of the piston and the latter is dependent entirely upon 45 the inner circulation of oil or water for its cooling. The fact that piston cracking is not uncommon after certain number of hours of service testifies to the extreme difficulty of this problem of cooling the piston. 50 In this new design all the scavenging air must come into intimate contact with the surface of the piston crown and will carry away much heat so that the internal cooling of the piston need not be as difficult to accomplish.

55 This method of scavenging is easily adapted for double acting engines, as may be seen from Figure 1. The outer surface of the piston rod is effectively cooled by the 60 scavenging air whirling around it, thus materially aiding its lubrication and protecting the stuffing box gland rings. Fuel valves 17^a which are arranged so that they follow the general direction of some one or 65 more scavenging ports, will not discharge

the fuel against the piston rod but into the whirling air of the combustion chamber, which whirling may be materially intensified by a suitable construction of the end 18 of the stuffing box protruding into the cylinder. These vanes or ribs shall also serve for the dissipation of heat to the scavenging air impinging upon them.

Fig. 5 shows my system of scavenging as applied to a so-called crankcase compression 75 engine where the amount of scavenging air is limited by the inevitable large clearance in the crank case and where an efficient system of scavenging is particularly desirable.

Although this new system of scavenging 80 is described above in its application to a type of engines that close their exhaust ports after the scavenging ports are closed, there is nothing in this specification that shall be construed as limiting its application to another type of engines which permits the scavenging ports to stay open after the exhaust ports are closed and thus produce the so-called supercharging effect. Fig. 6 illustrates such type of engine using 85 one or more valves 19 either mechanically operated or automatic in their action that keep the exhaust gases from entering the scavenging receiver while the exhaust ports are still closed.

Having described my invention what I claim as new is:

1. A scavenging system for internal combustion engines including a cylinder, a piston operable therein, a plurality of scavenging and exhaust ports in the cylinder, the scavenging and exhaust ports being respectively arranged on transverse lines with respect to the cylinder, the ports in one line being staggered with respect to the ports in the other line, ports in the piston coating with the scavenging ports in the cylinder, and means carried by the piston for producing a substantially solid column of scavenging fluid only.

2. A scavenging system for internal combustion engines including a cylinder, a piston operable therein, a plurality of tangential scavenging and exhaust ports in the cylinder, the scavenging and exhaust ports being respectively arranged on transverse lines with respect to the cylinder, the ports in one line being staggered with respect to the ports in the other line, ports in the piston coating with the scavenging ports in the cylinder, and means carried by the piston for producing a substantially solid column of scavenging fluid only.

3. A scavenging system for internal combustion engines including a cylinder, a piston operable therein, a plurality of scavenging and exhaust ports in the cylinder, each succeeding exhaust port being positioned above and to the side of the preceding scavenging port, ports in the piston co-

acting with the scavenging ports in the cylinder, each succeeding exhaust port being positioned above and to the side of the preceding scavenging port, tangential ports in the piston coacting with the scavenging ports in the cylinder, and means carried by the piston for producing a substantially solid column of scavenging fluid only.

5. 4. A scavenging system for internal combustion engines including a cylinder, a piston operable therein, a plurality of tangential scavenging and exhaust ports in the

cylinder, each succeeding exhaust port being positioned above and to the side of the preceding scavenging port, tangential ports in the piston coacting with the scavenging ports in the cylinder, and means carried by the piston for producing a substantially solid column of scavenging fluid only.

EDWARD C. MAGDEBURGER.
